SUPPORT RACK FOR TOOLS AND SMALL ARTICLES

Anne M. Searcy, Thomasville, Ga., assignor to
Handy Anne, Inc., Thomasville, Ga.

Filed June 25, 1970, Ser. No. 23,663

Term of patent 14 years

Int. Cl. D6—04

U.S. Cl. D33—3

FIG. 1.

FIG. 2.

FIG. 3.

FIG. 4.

FIG. 1 is a front perspective view of a support rack for tools and small articles showing my design.

FIG. 2 is a front elevational view thereof.

FIG. 3 is another front perspective view thereof.

FIG. 4 is a top plan view thereof.

The rear side of the support is plain.

I claim:

The ornamental design for a support rack for tools and small articles, as shown and described.
